[57] **CLAIM**

The ornamental design for an ornamental light collar for string light, as shown.

DESCRIPTION

FIG. 1 is a perspective view of the ornamental collar for string light of the present invention;

FIG. 2 is a top planar view of the ornamental collar for string light of the present invention;

FIG. 3 is a bottom planar view of the ornamental collar for string light of the present invention;

FIG. 4 is a side view of the ornamental collar for string light of the present invention; and,

FIG. 5 shows another side view of the ornamental collar for string light of the present invention as shown in FIG. 4 which has been rotated 60°.

The light bulb and wire are shown in broken lines for illustrative purposes only and form no part of the claimed design.

FIG. 1

FIG. 2

FIG. 3

FIG. 4

FIG. 5
